UNITED STATES PATENT OFFICE.

LOUIS VICTOR THOMAS AND JOSEPH-ALEXANDRE GUÉRIN, OF LYON, FRANCE,
ASSIGNORS TO SOCIÉTÉ ANONYME DU MOTEUR L. THOMAS, OF LYON,
FRANCE.

TWO-STROKE-CYCLE INTERNAL-COMBUSTION ENGINE.

1,388,390.

Specification of Letters Patent. Patented Aug. 23, 1921.

Application filed May 14, 1920. Serial No. 381,459.

(GRANTED UNDER THE PROVISIONS OF THE ACT OF MARCH 3, 1921, 41 STAT. L., 1313.)

To all whom it may concern:

Be it known that we, LOUIS VICTOR THOMAS and JOSEPH-ALEXANDRE GUÉRIN, citizens of the French Republic, and residents of Lyon, France, have invented certain new and useful Improvements in Two-Stroke-Cycle Internal-Combustion Engines, (for which we have filed an application in France, June 20, 1914, Patent No. 473,792,) 10 of which the following is a specification.

The invention relates to two stroke cycle internal combustion engines of the type wherein a piston works in part in a power or explosion cylinder and in part in a pump 15 chamber, with a slide or piston valve controlling the supply of fuel.

The invention is illustrated in the accompanying drawings in which—

Figure 1 is a vertical section of a twin cylinder engine wherein the improvements 20 constituting the invention are incorporated.

Fig. 2 is a vertical section taken in a plane perpendicular to that of Fig. 1.

Fig. 3 is a vertical section on the line 3—3 25 of Fig. 2.

A designates the piston valve, which is reciprocable in a cylindrical valve box S having a centrally disposed inlet port T, and toward each end two parts T¹ and T² 30 controlled by the valve so as to enable the lower enlarged parts of the pistons N to draw carbureted air or other gaseous fuel into the pump chambers B and then force the same into a gas chamber or reservoir C. 35 The latter communicates with the explosion chamber B¹ of the engine cylinder by means of a supply port T³. One part of the invention consists in arranging that the ends of the valve box form air-tight compartments 40 wherein air is compressed by the movement of the piston valve, the compressed air serving to cushion the valve at the ends of its path.

Another part of the invention consists in 45 effecting the actuation of the piston valve by means of a shaft arranged transversely of the crank shaft at or near one end thereof. The drawing shows the valve actuated by a lever D pivoted at E and rocked by an eccentric F and rod F¹. The eccentric is 50 mounted upon a shaft G placed transversely

of the crank shaft H and driven at the same speed as the shaft H by means of worm gears I and J. The worm wheel I is fixed to one end of the shaft H, outside the crank 55 case H¹, thus enabling the bearings of the shaft to be placed closely together and involving no loss of rigidity.

Another part of the invention consists in inclosing the shaft G in a gear box M disposed in front of the motor, joined to the crank case H¹ and having a detachable cover M¹ the said cover serving to protect the gear in the box but forming no part of the supporting structure. Outside the gear box the 60 shaft G drives the magneto K and lubricating pump L, and it may be used for driving other accessory mechanism associated with the motor. When the cover M¹ is removed 65 the gear in the box can be easily inspected. 70

Another part of the invention consists in providing the pistons N with piston rings P about midway between their ends, serving in part to increase tightness between the explosion chambers B¹ and the pump chambers B, and in part (and more especially) 75 to increase the tightness between the pump chambers B and the ports T³, perfect tightness of the pump chambers being essential to efficient working of the motor. In the 80 construction shown each piston has two piston rings P spaced somewhat apart.

Another part of the invention consists in providing within each piston an annular cup or well O, with ducts Q leading therefrom into a circular groove or channel R in the outer surface of the piston, between the rings P. The oil projected in the usual manner into the piston is collected in the 85 said well and flows through the ducts into 90 the channel R, in which it is retained by the rings P.

What we claim as our invention and desire to secure by Letters Patent of the 95 United States is:

In a two-stroke cycle internal combustion engine the combination of a cylinder having an explosion chamber and a pump chamber, a piston working in said chambers, a valve box having a gas inlet port, a gas delivery 100 port, and a port communicating with said pump chamber, a reciprocating slide valve

in said box controlling said ports, a crank shaft actuated by said piston a shaft arranged transversely to said crank shaft, actuating means connecting said crank shaft 5 to said transverse shaft, an eccentric on said transverse shaft lever mechanism connecting said eccentric to said valve whereby said valve is reciprocated, a magneto connected to said transverse shaft, a lubricating pump 10 connected to said transverse shaft, and a

box having a removable cover inclosing said transverse shafts and eccentric.

In witness whereof we have signed this specification in the presence of two witnesses.

LOUIS VICTOR THOMAS.
JOSEPH-ALEXANDRE GUÉRIN.
